UNITED STATES PATENT OFFICE.

GEORGE L. RAWDON, OF CLEVELAND, OHIO.

TELEGRAPH-REPEATER.

1,106,001.

Specification of Letters Patent.

Patented Aug. 4, 1914.

Application filed April 24, 1913. Serial No. 763,190.

To all whom it may concern:

Be it known that I, GEORGE L. RAWDON, a citizen of the United States of America, residing at Cleveland, in the county of Cuyahoga and State of Ohio, have invented certain new and useful Improvements in Telegraph-Repeaters; and I hereby declare the following to be a full, clear, and exact description of the invention, such as will enable others skilled in the art to which it pertains to make and use the same.

This invention relates to certain new and useful improvements in automatic telegraph repeaters and particularly to improvements on the repeaters shown in my Patent No. 914,877, dated March 9th, 1909, and in my Patent No. 1,048,209, dated December 24th, 1912, and has for its object to provide another mode of operation to produce more of the time element which insures the locking of the opposite relay before the main line current is removed from it, and its unlocking after the main line current has been restored, and thereby making the operation of the repeater more secure in preventing a kick or momentary flying back of the relay armature lever in cases where high tension spring adjustments are required in adjusting the relay to receive incoming signals.

My invention in part consists in providing a triple wound magnet in each main receiving relay by winding a third coil on the differential magnet of each main receiving relay, shown in my above referred to patents, and further providing the repeating sounders with auxiliary levers on which are placed the main line repeating points and the points for operating the third coils which are wound on the aforementioned differential magnets.

My invention also consists in the features of construction and combination of parts, hereinafter described in the specification, pointed out in the claims and illustrated in the accompanying drawing.

In the accompanying drawings is shown, somewhat conventionally, my improved telegraph repeater and the various electrical connections, wherein 10 represents one main line, which, for the sake of convenience, I shall call the east line, 11 the main receiving relay, 12 the repeating sounder and 13 the main battery of the west line. Likewise 10' represents the other main line, which I

shall call the west line, 11' the main receiving relay, 12' the repeating sounder and 13' the main battery of the east line.

The main receiving relay 11 is provided with a main electromagnet 14 in the east line, a triple wound magnet consisting of two oppositely wound coils 15 and 16 which form a part of a local circuit controlled in part by the opposite relay 11' and a third coil 15^a of no particular number of turns wound on the same core and in the same direction as the equal coil 15 that is always intact and not in the direction of the equal coil 16 that includes the break point of the opposite relay, and a pivoted armature lever 17 adapted to engage a front contact point 18 and a rear stop 19. A spring 20 is attached to the armature lever 17 and tends to pull the latter away from the contact point 18 and against the stop 19. The main receiving relay 11' is likewise provided with a main electro-magnet 14' in the west line, a triple wound magnet consisting of two oppositely wound coils 15' and 16' which form a part of a local circuit controlled in part by the opposite relay 11 and a third coil 15^b of no particular number of turns wound on the same core and in the same direction as the equal coil 15' that is always intact and not in the same direction as the equal coil 16' that includes the break point of the opposite relay, and a pivoted armature lever 17' adapted to engage a front contact point 18' and a rear stop 19'. A spring 20' is attached to the armature lever 17' and tends to pull the latter away from the contact point 18' and against the stop 19'.

The repeating sounder 12 is provided with an electro-magnet 21 located in the local circuit with the coil 16' controlled by the relay 11, also a pivoted armature lever 24. A spring 25 connected to the armature lever 24 tends to draw the armature lever against the stop 23 and away from a stop 23^a. In proximity to the armature lever 24 is mounted an auxiliary lever 24^a. The auxiliary lever 24^a carries a contact point 22 and a contact point 36 which are insulated from each other. The contact point 22 is arranged to make contact with the contact point on the end of the lever 24 and the contact point 36 is arranged to make contact with a point 35 which controls the circuit in the third coil. A spring 24^a is con-

nected with the lever 24^a and tends to pull the lever 24^a in the direction of the stationary contact point 35.

The repeating sounder 12' is provided with an electro-magnet 21' located in the local circuit with the coil 16 controlled by the relay 11' and also a pivoted armature lever 24'. A spring 25' connected to the armature lever 24' tends to draw the armature lever against a stop 23' and away from a stop 23''. In proximity to the armature lever 24' is mounted an auxiliary lever 24^b. The auxiliary lever 24^b carries a contact point 22' and a contact point 36' which are insulated from each other. The contact point 22' is arranged to make contact with the point on the end of the lever 24' and the contact point 36' is arranged to make contact with the stationary point 35'. A spring 24^a is connected with the lever 24^b and tends to pull the lever 24^b in the direction of the stationary contact point 35'.

I shall now describe the two local circuits which I employ in my repeater. The one local circuit is provided with a battery 26 which is connected by conductors 27 to a point at which the circuit divides and to the coils 15 and 16 of the differential magnet which coils are in parallel to each other or in the opposite legs of the divided circuit. The coil 16 is connected by a conductor 28 to the contact point 18' of the main receiving relay 11' and the armature lever 17' of the same relay is connected by a conductor 29 to one terminal of the coil 21', the other terminal of the coil 21' being connected to a point *m* by a conductor 29^a.

The terminal of the coil 15 is connected by a conductor 33 to the point *m*. The terminal of the coil 15^a is connected by a conductor 34 to contact point 36' on auxiliary lever 24^b. The contact point 35' is connected by conductor 37 to a point *m* and included in conductor 33 is an artificial resistance 31'. The other terminal of the battery 26 is connected by a conductor 32 to the point *m*.

The coil 16' is connected by a conductor 28' to the contact point 18 of the main receiving relay 11 and the armature lever 17 of the same relay is connected by a conductor 29' to one terminal of the coil 21, the other terminal of said coil 21 being connected to a point *m'* by a conductor 29^b. The terminal of the coil 15' is connected by a conductor 33' to the point *m'* and in said conductor is included an artificial resistance 31. The terminal of the coil 15' is connected by a conductor 34' to the contact point 36 on auxiliary lever 24^a. The contact point 35 is connected by conductor 37' to point *m'*. The other terminal of the battery 26' is connected by a conductor 32' to the point *m'*.

Under normal conditions and when 65 neither line is in use, both local circuits in

the two oppositely wound equal coils are closed, the armature lever of each main receiving relay being held onto the front contact point against the tension of the spring by the magnetizing effect of the main magnet coil, the magnetizing effects of the two oppositely wound equal coils being nil, as one coil neutralizes the other, while the circuit in the winding of the third coil is open in the points on the upper end of the auxiliary levers 24^a and 24^b. If the operator on the east line opens the east line, the armature lever 17 of the eastern relay will be pulled away from its front contact point 18 by the relay spring 20 opening the circuit in one of the equal coils of one branch or leg of the local circuit, and permitting the other coil in the other branch or leg, by its magnetizing effect to prevent the armature lever of the western relay from being drawn away from its front contact point. As soon as the eastern relay armature lever leaves its front contact it also opens the circuit in the coil of the repeating sounder which permits the spring of the repeating sounder to draw its armature lever away from its front contact point, releasing the auxiliary lever and causing the points on the upper end of the auxiliary lever to strike together, thereby closing the circuit in the third coil of the auxiliary magnet of the opposite relay. When the points on the upper end of the auxiliary lever strike together and the repeating sounder armature lever continues on its backward stroke, the points on the lower end of the auxiliary lever and on the upper end of the repeating sounder armature lever, are parted, thereby breaking the main line circuit and causing the signal to be transmitted to the west line. As the third coil is wound in the same direction as the equal coil, that is always intact, it is apparent that after the circuit in the third coil has been closed, its magnetic effect is the same as that of the equal coil that is always intact, and the western relay armature lever is now held closed by the joint magnetic effects of the third coil and the equal coil that is always intact, the circuit in the equal coil that includes the break points of the eastern relay armature lever, having been previously opened by the eastern relay armature lever. The reverse operation, or the restoring of the main line current and the unlocking of the opposite relay is described as follows:—If the operator of the east line closes the east line, the relay armature lever 17 is drawn onto its front contact against the tension of the relay spring, closing the circuit of the repeating sounder coil 21 and drawing the repeating sounder armature lever 24 toward its front contact, against the tension of the repeating sounder spring, causing the point on the upper end of the repeating sounder lever to strike the point 130

on the lower end of the auxiliary lever 24^a, thereby restoring the main line current.

When the main line repeating points strike together, the repeating sounder armature lever continues on toward its front stop 23^a, forcing the auxiliary lever forward, breaking the circuit in the third coil at the points 35 and 36 on the upper end of the auxiliary lever, demagnetizing it, thereby unlocking the western relay, as the two oppositely wound equal coils neutralize each other.

When the eastern relay armature lever reaches its front contact which closes the circuit in the equally wound coil it had previously opened in locking the western relay, it does not unlock the western relay, as the magnetic effect of the third coil holds the western relay armature lever closed until the circuit in the third coil is opened in the points 35 and 36 on the upper end of the auxiliary lever 24^a.

What I claim is,—

1. In a telegraph repeater, a pair of receiving relays, each having a repeating sounder, a main magnet and a triple wound magnet and means whereby the armature lever of one relay and the armature lever of the same relay's corresponding repeating sounder controls directly two coils of the triple wound magnet of the other relay.
2. In a telegraph repeater, a pair of repeating sounders, a pair of receiving relays, each relay having a main magnet and a triple wound magnet, two coils of said triple wound magnet being equal and oppositely

wound, means whereby the armature lever of one relay controls directly one of said two equal and oppositely wound coils of the triple wound magnet of the other relay, and means whereby the third coil or remaining coil of the same triple wound magnet is controlled directly by the armature lever of one of the said repeating sounders.

3. In a telegraph repeater, a pair of receiving relays, each having a repeating sounder, a main magnet and a triple wound magnet, two coils of which are equal and oppositely wound, means whereby the armature lever of one relay controls directly the equal coil of the triple wound magnet of the other relay which is wound oppositely from the equal coil which is always intact and means whereby the third or remaining coil of the same triple wound magnet is controlled directly by the armature lever of one of the repeating sounders.

4. In a telegraph repeater, a receiving relay having a main magnet and a triple wound magnet, the triple wound magnet having two equal and oppositely wound coils, one of which is always intact, and a third coil which is wound in the same direction as the coil which is always intact of the said two equal and oppositely wound coils.

In testimony whereof, I sign the foregoing specification, in the presence of two witnesses.

GEORGE L. RAWDON.
